UNITED STATES PATENT OFFICE.

WILLIAM GRIMSHAW, OF GLENELLYN, ILLINOIS.

FIRE-EXTINGUISHER.

Specification of Letters Patent.

Patented Mar. 18, 1919.

1,297,559.

Application filed April 15, 1918. Serial No. 228,608.

To all whom it may concern:

Be it known that I, WILLIAM GRIMSHAW, a citizen of the United States, and a resident of Glenellyn, in the county of Dupage 5 and State of Illinois, have invented a new and useful Fire-Extinguisher, of which the following is a specification.

This invention relates to fire extinguishers and relates particularly to fusible members 10 for automatic sprinklers and similar purposes.

The object of the present invention is to provide a fusible member for the purpose specified, which shall be simple in construction, strong, durable and effective for its 15 designed purpose. To effect this object, a fusible member of my invention comprises the various features and details of construction hereinafter described and claimed.

20 In the accompanying drawing, in which my invention is fully illustrated,

Figures 1 and 2 are, respectively, front and rear face views, on an enlarged scale, 25 of opposite sides of a fusible member embodying my invention.

Fig. 3 is a side or edgewise view thereof.

Fig. 4 is a longitudinal sectional view thereof on the line 4—4 of Fig. 1; and

Fig. 5 is a transverse sectional view there- 30 of on the line 5—5 of Fig. 4.

Referring now to the drawings, my improved fusible member, designated as a whole *a*, consists of two plates 1 and 2 soldered together, said plates being preferably 35 stamped from sheet phosphor-bronze or other suitable sheet metal, and being of proper width and thickness to afford requisite strength. When operating in tension, said plates 1 and 2 are preferably stamped 40 from metal of about 17 gage.

As shown, said plates 1 and 2 are counter- 45 parts of each other, being of the same size and shape, thus requiring but one set each of blanking and swaging dies for forming of the same, and are symmetrical on both sides of a longitudinal center line.

As shown, also, said fusible member is 50 adapted to be applied through the medium of toggle arms indicated in dotted lines at 3 and 4, Fig. 4, the relation being such that to said fusible member will act in tension. To provide for engaging the toggle arms 3 and 4 with said fusible member *a* and to permit said toggles to separate when said mem- 55 ber fuses, each of the plates 1 and 2 is provided with a hole 5 in one end thereof and

a slot or notch 6 in its opposite end, and are soldered together with the slot 6 in one thereof in register with the hole 5 in the other, thus providing for pulling said plates 60 apart endwise, as contemplated.

To strengthen the connection between the plates 1 and 2 and thus correspondingly relieving the stress on the solder joint connecting said plates, said plates are provided 65 with interlocking shoulders 7 and 8 formed on the overlapping connected ends of said plates, the male shoulders 7 being formed at the ends of portions of said plates struck up from the connected sides or faces thereof, shown at 9, and the female shoulders 8 being formed at the ends of recesses struck back from the connected sides or faces of said plates, as shown at 10. As shown, there are two sets of said opposite shoulders 7 and 8, the male and female shoulders of each 75 of said sets of shoulders being formed, respectively, on different plates and the shoulders of each set facing in opposite directions.

Said shoulders 7 and 8 will be inclined 80 relatively to the planes of the connected sides of the plates 1 and 2, the angle of inclination being such that tension applied to said plates will produce a desired component of force tending to effect disengagement 85 of said shoulders and to force said plates apart. For general uses, a desirable angle of inclination of said shoulders to the planes 90 of the connected faces of said plates is about sixty (60) degrees.

In the preferable construction shown, also, 95 the sides of the portions of said plates between the shoulders 7 and 8 thereon, respectively, are disposed in planes which are inclined to the planes of the sides of the plates of which they are parts, the angles of inclination depending upon the distance between the different sets of shoulders and the distance which they project from the faces of 100 said plates, both of which dimensions may vary within considerable limits, thus producing a corresponding variation in the inclinations of said plates between the shoulders thereon and the sides or faces thereof. 105

Obviously, by facing the interlocking shoulders on the plates 1 and 2 in opposite directions to those shown in the drawings, said fusible member can be readily adapted 110 for use in compression instead of in tension.

I claim:

1. A fusible member comprising plates

soldered together in overlapped position, said plates comprising portions in their overlapping ends which are inclined at a small angle to the plane of the connected sides thereof, the ends of said inclined portions forming projections on opposite sides of said plates, each of which is provided with a recess on the reverse side of said plate, said projections on and recesses in the connected sides of said plates forming interlocking shoulders, said shoulders being inclined to the plane of the connected sides of said plates at angles slightly less than right angles, the relation being such that when 15 said fusible member is subjected to endwise stress in opposition to said shoulders, said shoulders will produce components of force tending to effect disengagement of said shoulders and separation of the plates forming said fusible member, substantially as described.

2. A fusible member comprising plates soldered together in overlapped position, said plates comprising portions in their overlapping ends inclined at small angles to the plane of the connected sides thereof, opposite ends of which are symmetrical at opposite sides of said plane of connection and of the transverse centers of said inclined portions, the ends of said inclined portions forming projections on opposite sides of said plates, each of which is provided with a recess on the reverse side of said plate, the 30 projections on and recesses in the connected sides of said plates forming interlocking shoulders which are inclined to the plane

of the connected sides of said plates at angles slightly less than right angles, whereby when said fusible member is subjected to endwise stress in opposition to said shoulders, said shoulders will produce components of force tending to effect disengagement of said shoulders and separation of the plates forming said fusible member, substantially as described.

3. A fusible member comprising plates soldered together in overlapped position, said plates comprising portions in their overlapping ends which are inclined to the plane of the connected sides thereof at angles of substantially 30 degrees, the ends of said inclined portions forming projections on opposite sides of said plates each of which is provided with a recess on the reverse side of said plate, the projections on and recesses in the connected sides of said plates forming interlocking shoulders which are inclined to the plane of the connected sides of said plates at angles of substantially 60 degrees, whereby when said fusible member is subjected to endwise stress in opposition to said shoulders, the inclination of said shoulders will produce components of force tending to effect disengagement of said shoulders and separation of the plates forming said fusible member, substantially as described.

In testimony, that I claim the foregoing as my invention, I affix my signature this 5th day of April, A. D. 1918.

WILLIAM GRIMSHAW.
